Primary Examiner—Melanie H Tung(74) *Attorney, Agent, or Firm*—Martine Penilla & Gencarella, LLP(57) **CLAIM**

The ornamental design for a computer user interface for a display screen, as shown and described.

DESCRIPTION

The single FIGURE is a front view of a computer user interface for a display screen showing our new design.

The broken line showing of a display screen, images and text form no part of the claimed design.

1 Claim, 1 Drawing Sheet
